UNITED STATES PATENT OFFICE.

EDWARD T. CROOKER, OF COLUMBUS, OHIO.

CALENDAR.

Application filed August 22, 1924. Serial No. 733,581.

To all whom it may concern:

Be it known that I, EDWARD T. CROOKER, a citizen of the United States, residing at Columbus, in the county of Franklin and 5 State of Ohio, have invented certain new and useful Improvements in Calendars, of which the following is a specification.

This invention relates to improvements in perpetual calendars and has as its general object to provide a calendar extremely simple in construction, capable of ready adjustment of its component parts to properly display the calendar indicia, and possessing numerous advantages over calendars of this 15 class which have heretofore been designed.

Another object of the invention is to provide a perpetual calendar which, so far as exterior appearance is concerned, will be not only attractive but will, so far as the 20 calendar indicia is concerned, not differ in its appearance from any ordinary calendar.

The calendar embodying the invention is of that type in which month date bearing panels are employed and are so suspended that they 25 may be selectively arranged in accordance with any month of any year, and another object of the present invention is to provide a novel means for supporting such panels which means will be extremely simple in its 30 construction and permit of the most ready arrangement of the panels as occasion will require at the beginning of each month.

Another object of the invention is to so construct the calendar that it will occupy but 35 little space when hung upon a wall or supported in any other manner, and will be devoid of the bulky appearance possessed by other calendars of this general class.

In the accompanying drawings:

40 Figure 1 is a view in front elevation of a calendar constructed in accordance with the invention, the calendar being shown closed.

Figure 2 is a similar view showing the calendar open.

45 Figure 3 is a vertical front to rear sectional view on the line 3—3 of Figure 1, looking in the direction indicated by the arrows.

50 Figure 4 is a view similar to Figure 3, illustrating a slight modification of the invention.

Figure 5 is a view similar to Figure 1, illustrating a modified form of the invention.

55 Figure 6 is a vertical front to rear sec-

tional view taken substantially on the line 6—6 of Figure 5.

Figure 7 is a perspective view of the marker shown in Figures 5 and 6 of the drawings.

The calendar embodying the invention comprises a frame structure which is indicated in general by the numeral 1 and which is preferably of the rectangular form shown in the drawings and includes side 65 members 2, a top member 3, and a bottom member 4. The frame structure may be provided with a back, if desired, although this is by no means essential inasmuch as, when the calendar is hung upon a wall or 70 otherwise supported against a flat surface, the back of the frame structure will be closed. As heretofore stated, the calendar is of that type embodying a number of month date bearing panels and these panels are 75 indicated in the drawings by the numeral 5 and the panels may be of wood, metal, or any other material found suitable for the purpose. Each panel is in the nature of a flat-sided strip, the longitudinal edges 80 of which are parallel, and each panel is provided at its lower end with a handle portion 6 by which the panel may be readily grasped for the purpose of manipulating the same in effecting a rearrangement of the 85 various panels at the beginning of each month. For a purpose which will presently be made clear, each panel is formed in its upper end portion with a vertically extending slot indicated by the numeral 7, the 90 slot extending midway between the longitudinal edges of the panel and parallel thereto. Each panel bears upon each of its faces a vertically arranged series of ordinals indicated by the numeral 8, representing month dates and the arrangement of these date ordinals upon the faces of the several panels will be such that by suitably interchanging and arranging the panels, any desired monthly calendar may be obtained.

95 The means provided for suspending the panels 5 comprises a pair of supporting rods 9 and 10 which are mounted at their ends preferably in the side members 2 of the frame structure and extend in horizontal 100 parallel relation to each other and beneath the top of the member 3 of the said frame structure, the rod 9 being arranged above the rod 10 and both rods occupying the same vertical plane. Each rod is formed at in-

tervals, upon its side which is presented toward the open side of the frame structure, with suspension hooks 11 which curve forwardly and thence upwardly as clearly shown in Figures 2 and 3 of the drawings. The hooks of the two rods are so spaced and arranged that respective hooks will be in vertical alinement throughout the two series. The slots 7 in the panels 5 are of dimensions to accommodate the hooks 11 and the said slots are likewise of a length greater than the distance between respective ones of the hooks upon the upper and lower rods. Such being the case, these panels may be suspended from the hooks upon the upper rod 9 or from the hooks upon the lower rod 10, and in the former instance, the hooks upon the upper rod 9 will engage the upper end walls of the slots and the slots will accommodate the respective hooks upon the lower rod 10. Of course, in the other instance, the hooks upon the lower rod 10 will engage the upper end walls of the slots 7. In view of the fact that the panels 5 may be supported at different elevations and certain of the panels bear upon their opposite faces a series of month date ordinals, a sufficiently wide range of adjustment is afforded to permit of display of a calendar month of twenty-eight, twenty-nine, thirty or thirty-one days, as may be necessary, and, likewise, the first day of the month may be arranged beneath the week day abbreviations which will presently be referred to.

The panels 5 are not suspended for free swinging movement but near their ends they rest at their rear sides against a cross rod 12 which is mounted at its ends in the side member 2 of the frame structure 1 and is located a suitable distance above the bottom member 4 of the said frame structure. This cross rod prevents any rearward swinging movement of the panels which might otherwise take place, and forward swinging movement of the panels is prevented in a manner which will now be explained.

The means referred to above comprises a panel 13 which may be of sheet metal, wood, or any other material or combinations of materials found suitable for the purpose, and this panel is of rectangular form and of a width equal to the width of the frame structure and is hingedly mounted at one end as at 14, upon one of the side members 2 of the said structure, the panel being so positioned that when swung to closed position as illustrated in Figure 1 of the drawings, it will extend across the lower portion of the open front of the frame structure and will cover and conceal the handle portions 6 of the month date panels 5. The outer face of the panel may bear any advertising matter desired, as indicated by the numeral 15, and the said panel 13 may be held closed at its free end by any suitable latch device indi-

cated by the numeral 16. Likewise, the face of the panel may be ornamented in any desired manner or the panel, if of sheet metal, may be suitably embossed. The inner face of the panel 13 bears a calendar indicated in general by the numeral 17 and the said calendar comprises columns of years indicated by the numeral 18, the years ranging consecutively and covering any desired period of years. Associated with each year column 18 is a horizontal roll 19 of month names including the twelve months of the year, this roll being located above the upper end of the respective year column 18 and extending laterally toward the right from said roll. Above each month name in the roll 19 is printed, as at 20, the number of days in the respective month. Extending vertically beneath each month name in the roll 19 and opposite the year dates in the column 18, is a column 21 of week day names and the arrangement is such that by glancing at this calendar and noting the current year, the user of the calendar may determine the day of the week on which the first day of any month of that year will fall and can accordingly adjust or rearrange the panels 5 to construct the monthly calendar. At this point it will be evident that when the panel 13 is swung to closed position, which position it will normally occupy, the calendar 17 will be concealed from view, it being only necessary, therefore, to swing the panel to open position at the first of each month when it becomes necessary to rearrange the panels 5.

The upper or slotted ends of the month date panels 5 are covered and concealed by a panel 22 which corresponds substantially in dimensions to the panel 13 and which may be of any material found suitable for the purpose. As illustrated in Figure 3 of the drawings, this panel 22 may comprise a sheet or ply 23 of metal, veneer, or any other suitable material, upon which may be printed the name of the calendar, as indicated by the numeral 24, or any other matter desired, the said sheet 23 being provided near its lower margin with openings 25 and 26 which are preferably of rectangular form as shown in Figure 1 of the drawings. The numeral 27 indicates a backing of sheet metal or other suitable material which is secured to the inner or rear face of the sheet 23 and preferably is of the same marginal dimensions as said sheet so that the margins of the two sheets are in registration with each other. The backing sheet 27 is stamped or otherwise formed to provide a pocket 28 extending longitudinally of the rear side of the panel as a whole and the wall of this pocket defined by the stamped out portion of the said backing sheet 27, is formed with openings 29 and 30 which are located respectively opposite the openings 25 and 26. Slidably and removably fitted into the

5 pocket 28 are two cards, one indicated by the numeral 31 and the other by the numeral 32, these cards being of oblong rectangular form and the said cards respectively bearing month abbreviations and year dates as indicated 10 respectively by the numerals 33 and 34. The months abbreviations and the year dates are printed upon the opposite faces of the cards and the indicia upon each face of each 15 card are so arranged as to be correctly readable when the longitudinal edge of the card next adjacent which the indicia are located is disposed lowermost within the pocket 28. Inasmuch as the cards 31 and 32 are not only 20 slidably adjustable within the pocket but also removable therefrom, the cards may be so arranged as to display any month in the year in which the calendar is used and likewise the correct year date. At this point it 25 will be evident that by providing the openings 29 and 30 in the rear wall of the pocket 28, the adjustment of the cards 31 and 32 is greatly facilitated.

25 The panel 22 is hingedly mounted at one end, as at 35, upon one of the side members 2 of the frame structure 1, and is normally held closed by any suitable latch 36 at its opposite end. As stated, the panel covers or conceals the upper or slotted ends of the 30 month date panels 5, and printed upon the face of the said panel 22 along the lower margin thereof, is a row 37 of week day abbreviations or names, these being located immediately above the columns of month date 35 ordinals upon the respective panels 5, as clearly shown in Figure 1. Upon the inner face of the panel 22 above the pocket 28 there may be printed, as at 38, the dates on 40 which Easter Sundays occur throughout a period of years.

45 From the foregoing description of the invention, it will be understood that the calendar when the panels 13 and 22 are closed, presents substantially the appearance of an ordinary monthly calendar, no indication being given that it is in effect, a perpetual calendar.

50 Figure 4 of the drawings, illustrates a slight modification of the invention with respect to the means provided to prevent rearward swinging movement of the lower ends of the month date panels 5, and in this figure the numeral 40 indicates one of the month date panels, the numeral 41 the frame structure in which the panels are suspended, the numeral 42 the lower covering panel which is the equivalent of the panel 15, and the numeral 43 a rod which is rotatably 55 journaled at its ends in the side members of the frame structure 41. This rod, as in the case of the rod 12, constitutes a rest against which the lower end portions of the month date panels may engage, but in this case 60 the rod is provided with a depending flange 44 which is normally out of contact with the

panels 40 but which, through manual rotation of the rod 43 as, for example, by the provision of any suitable fingerpiece at one or both ends of the rod, will be swung upwardly and forwardly to outwardly swing 70 the lower ends of the month date panels so that they may be more readily grasped. This arrangement provides for a more compact form of calendar, as will be evident by reference to Figure 4 and a comparison of 75 this figure with Figure 3.

In rearranging the month date panels at the beginning of any month, the panel next following the last day of expired month is removed and the panel bearing the ordinal 80 representing the first day of the month is substituted therefor, all of the other panels being then rearranged so that the month dates will read consecutively throughout. Reference may then be had to the calendar 85 data 17 upon the door 13 for the purpose of verifying the rearrangement of the panels.

The modified structure shown in Figures 5, 6 and 7, embodies a marker which is designed to be selectively disposed at different 90 points in the area occupied by the month date panels so as to indicate to the observer the current month date, and in the modified structure, which is otherwise substantially structurally identical with that previously described, the frame of the structure is indicated in general by the numeral 45 and comprises side members 46 corresponding to the side members 2 of the previously 95 described form. The month date panels are indicated by the numerals 47, and said panels are provided in their longitudinal edges with substantially semi-circular notches 48 located at the corners of the spaces in which the month date ordinals are printed, the said 100 notches, when the panels are arranged side by side as shown in Figure 5, being designed to register with corresponding adjacent notches so as to provide substantially circular openings between the adjacent edges of 105 adjacent panels. Likewise, the inwardly presented faces of the sides 46 of the frame 45 are formed with substantially semi-circular 110 grooves or notches 49 with which the notches in the edges of the endmost panels are designed to register, as shown in the said Figure 5. The marker is shown most clearly in Figure 7 of the drawings and is indicated in general by the numeral 50, and the said marker comprises a rectangular 115 frame 51 which is of dimensions substantially equal to the dimensions of the space within which any one of the month date ordinals of the month date panels are printed. This frame may be of metal and of any appropriate color to contrast with the surface defined by the group of panels, and projecting rearwardly from the upper corners of the frame are substantially cylindrical pins 52 which 120 are adapted to be fitted into the openings 125 130

formed by the registering notches at the upper corners of any of the month date spaces, the marker being, in this manner, supported upon the face of the panel assemblage in position to surround and enclose any one of the month date spaces of the panels. In order that the marker may be readily removed and repositioned, it is preferable that notches 53 be formed in the outer sides of the side members of the marker frame 51, as clearly shown in Figures 6 and 7 of the drawings, so that the thumb nail and forefinger nail may be engaged with the marker frame to permit of such removal and repositioning of the frame.

Having thus described the invention, what I claim is:

1. A calendar of the class described comprising a frame, spaced upper and lower supporting members extending transversely within the upper portion of the frame, suspension elements upon the said members, respective ones of the elements being arranged above one another, and month-date panels having slots in their upper portions of a length greater than the distance between two respective ones of the said suspension elements whereby each panel may be suspended from either of two associated ones of said elements, the slot in each panel accommodating the lower element when the panel is suspended from the upper element.
2. A calendar of the class described comprising a frame, spaced series of suspension

elements within the frame, the series of elements extending transversely in parallelism and the elements of each series being correspondingly spaced, and month-date bearing panels having slots in their upper end portions of a length greater than the distance between the two series of elements, whereby each panel may be suspended selectively from the upper and the lower corresponding elements of the two series.

3. A calendar of the class described comprising a frame, spaced series of suspension elements within the frame, the series of elements extending transversely in parallelism near the upper end of the frame and the elements of each series being correspondingly spaced, month date bearing panels having openings in their upper end portions of dimensions to accommodate two of the suspension elements in one position of vertical adjustment of the panels and to accommodate a single one of the elements in another position of adjustment of the panels, whereby each panel may be suspended selectively from the upper and lower corresponding elements of each series, and cover members hingedly mounted at one side of the frame, one at the top thereof and the other at the bottom thereof and, when closed, constituting means to retain the said month date bearing panels in the position to which they have been adjusted.

In testimony whereof I affix my signature.

EDWARD T. CROOKER. [L. s.]
